CLAIM

The ornamental design for a man basket as shown and described.

DESCRIPTION

FIG. 1 is a top perspective view of a man basket showing the new design.

FIG. 2 is a bottom perspective view of a man basket showing the new design.

FIG. 3 is a front view of a man basket showing the new design.

FIG. 4 is a rear view of a man basket showing the new design.

FIG. 5 is a first side view of a man basket showing the new design.

FIG. 6 is a second side view of a man basket showing the new design.

FIG. 7 is a top view of a man basket showing the new design.

FIG. 8 is a bottom view of a man basket showing the new design; and,

FIG. 9 is a top perspective view of a man basket showing the new design with the telescoping arms in an extending position and the material jig in an upwardly rotated position. The broken line description show portions of the man basket which form no part of the claimed design.
